Patented Mar. 30, 1915.

UNITED STATES PATENT OFFICE.

HERMAN W. BECHT, OF DAYTON, AND EDWARD C. BECHT, OF NEWPORT, KENTUCKY.

CONFECTIONERY-COATING MACHINE.

1,133,789.

Specification of Letters Patent. Patented Mar. 30, 1915.

Application filed January 13, 1913. Serial No. 741,611.

To all whom it may concern:

Be it known that we, HERMAN W. BECHT and EDWARD C. BECHT, the first residing at Dayton and the other at Newport, both in Campbell county, State of Kentucky, have invented certain new and useful Improvements in Confectionery-Coating Machines; and we do declare the following to be a clear, full, and exact description of the invention, attention being called to the drawing which accompanies this application and forms a part thereof.

This invention concerns improvements in machines for coating confectionery, the improvements concerning more particularly a device for moving the objects to be coated in position for this purpose and to carry them away again after having been coated, affording meanwhile possibility for the surplus of the coating substance to drain freely away.

The invention consists of the construction of the device as hereinafter described and claimed and as illustrated in the accompanying drawing, in which:

Figure 1, shows our device in longitudinal section. Figs. 2, 3 and 4, in similar views show the same in various positions which it successively assumes during operation. Fig. 5, is part of a top-view of the device and Fig. 6, is a transverse section of it taken on line 6—6 of Fig. 1.

The device consists substantially of spaced, parallel bars having straight upper edges arranged in two sets, each of which constitutes a grate.

A—A, designate the bars of one of these grates, they being connected at their opposite ends to a frame *a*, which occupies a stationary substantially horizontal position.

B—B designate the bars of the other grate which is supported so as to be capable of an operative movement with respect to the first grate, this movement being in a manner that the bars of the movable grate occupy alternately positions above and below the bars of the stationary grate, they passing up and down between them. The bars of each set are so closely spaced, that any two adjoining bars of either set are capable of supporting between them centers to be coated.

The movement of these closely spaced bars is rendered possible by making the thickness, or size vertically considered, of the movable grate bars greatly in excess of the thickness of the bars of the stationary grate and by supporting them accordingly. For

such purpose they are mounted, each near each of its ends, upon rods 8 and 9, arranged parallel to each other, the connection of these rods to the bars being so as to permit them to turn freely at the points of their engagement with the bars. These rods are carried by the free ends of parallel crank-arms, rod 8 being carried between arms 11—11, and rod 9 being carried by arms 12—12. Each of these arms is provided with a journal, 13—13 being the journals of arms 11, and 14—14 being those of arms 12. Each set of these journals is supported in axially alined, opposite bearings, properly positioned below the stationary grate and provided in a suitable frame.

It will now be seen that if rods 8 and 9 are rotated in unison about their journals, bars B will be moved with respect to bars A in the manner indicated by the arrows. This rotation may be by suitable power applied to one of the journals of one of the rods from which it is transmitted to one of the journals of the other rod by means of a chain 15 in engagement with chain-wheels 16—16, one mounted upon one journal of each rod.

17 is a belt shown in Fig. 1, which supplies the objects to be coated, which for instance may be chocolate-centers C. This belt is substantially as wide as the grates and supplies the centers upon them, as best shown in Fig. 1. They are picked up as shown in Fig. 2, carried forward as shown in Fig. 3, and deposited in an advanced position upon the bars of the stationary grate as shown in Fig. 4. During the succeeding rotation they are picked up again and carried forward as before, which action is repeated, the centers being advanced step by step until they are finally shoved off. They may discharge upon a suitable off-bear device which may be another belt 18 as shown in Fig. 1, whereby they are carried away. While thus passing forward they are coated with a substance which discharges at 19, which is the outlet from a supply tank 20. The step by step advance of the centers over the grates affords ample time for surplus coating material to drain away, thus giving the centers an even covering. The surplus drips into a tank 21 and preserves it against waste. Other conditions admitting it, this matter may be re-used at any time, or immediately by being raised up to tank 20. The under side of the centers becomes coated by contact with the upper

edges of the bars which necessarily are covered with coating material which discharges from the tank and drops between the centers and also with such material which drains upon said bars from the coated centers as they are being advanced. Inasmuch as the centers rest upon these material-covered edges and are also constantly changing positions thereon while being carried forward, material is picked up by them with every change of their positions. Material thus taken up is not disturbed and readily adheres since no movement takes place between any center and the particular portion of the bar upon which it rests.

Arms 12-12, which support rod 9 are not as long as arms 11, and this rod engages bars B in slots 22. The result is that toward the discharge end of the grates, bars B are not raised as high but receive a forward sliding movement which favors the passing off of the coated centers from the grates upon belt 18. Bars B may be serrated at their upper edges as shown at b, the serrations however being so closely spaced that as a support for the centers said bars still present substantially straight edges, so that said centers are prevented from toppling over, or from sliding on the bars which would interfere with the adherence of coating material on their underside.

Having described our invention, we claim as new:

1. In a confectionery coating machine, comprising a tank adapted to discharge coating material upon centers to be coated and a drainage tank below the same, the combination of two sets of parallel bars positioned between these two tanks, the bars in these sets being spaced so closely that any two adjoining bars of either set are adapted to support centers between them, the upper edges of these bars providing straight supports for such centers, one set of these bars being supported substantially horizontal in a stationary position, two rods supported transversely below the stationary bars and upon which the bars of the other set are mounted at each of their ends, the engagement being such as to permit rotation of these rods with respect to these bars which they support, an arm at each end of each of these rods whereby they are carried, a journal on each arm, a bearing for each journal and means to actuate these rods in unison with a rotary movement about the journals of the arms which carry said rods and whereby the bars mounted upon these rods are alternately raised and lowered, the thickness of these bars, vertically considered, being such that when raised they are above the stationary bars.

2. In a confectionery coating machine, comprising a tank adapted to discharge coating material upon centers to be coated and a drainage tank below the same, the combination of two sets of parallel bars positioned between these two tanks, the bars in these sets being spaced so closely that any two adjoining bars of either set are adapted to support centers between them, the upper edges of these bars providing straight supports for such centers, one set of these bars being supported substantially horizontal in a stationary position, two rods supported transversely below the stationary bars and supporting the bars of the other set at their ends, the engagement of one rod being in closely fitting openings in said bars and the engagement of the other rod being in longitudinally arranged slots, arms of equal length supporting the rod first mentioned, shorter arms also of equal length supporting the other rod, a journal on each arm, a bearing for each journal and means to rotate these rods in unison about the journals of their supporting arms.

3. In a confectionery coating machine, comprising a tank adapted to discharge coating material upon centers to be coated and a drainage tank below the same, a set of parallel bars positioned between these two tanks and spaced so that any two adjoining bars are adapted to support centers to be coated, a conveyer for moving chocolate centers supported at each end of the set of these bars and so as to be substantially in alignment with the upper edges of these bars, means to actuate these conveyers so that both move in the same direction, another set of parallel bars also spaced so that any two of them, adjoining, are adapted to support centers to be coated and means to actuate the bars of this set so that they alternately rise above the upper edges of the stationary bars and also move alternately between the ends of the conveyers, this latter movement being so that above the stationary bars it is in a direction substantially like that in which the conveyers move so that centers moved upon the stationary bars by one conveyer are picked up by these movable bars and carried step by step to the other conveyer to be received by the same.

In testimony whereof we hereunto affix our signatures in the presence of two witnesses.

HERMAN W. BECHT.
EDWARD C. BECHT.
